UNITED STATES PATENT OFFICE.

ALFRED A. TURNAGE, OF SAN JOSE, CALIFORNIA.

JEWELER'S TOOL.

1,172,571.

Specification of Letters Patent. Patented Feb. 22, 1916.

Application filed July 29, 1915. Serial No. 42,597.

To all whom it may concern:

Be it known that I, ALFRED A. TURNAGE, a citizen of the United States, residing at the city of San Jose, in the county of 5 Santa Clara and State of California, have invented certain new and useful Improvements in Jewelers' Tools; and I do declare the following to be a full, clear, and exact description of the invention, such as will enable others skilled in the art to which it 10 appertains to make and use the same.

My invention relates broadly to improvements in tools, the subject matter of the present application being designed, however, 15 for the use of jewelers and watchmakers, the device being so constructed as to provide a number of so called bench keys of various sizes, confined normally within a magazine, but capable of projection therefrom for the 20 winding of watch movements of various designs.

The object of the invention is to provide a tool which although being extremely simple and therefore inexpensive, will be highly 25 efficient and durable and will possess a number of advantageous characteristics.

With this general object in view, the invention resides in certain novel features of construction and in unique combinations of 30 parts to be hereinafter fully described and claimed, the descriptive matter being supplemented by the accompanying drawings wherein like reference characters designate corresponding parts throughout the several 35 views and wherein:

Figure 1 is a side elevation of a tool constructed in accordance with my invention; Fig. 2 is an enlarged vertical longitudinal section thereof showing one tool shank retracted and confined in the magazine; Fig. 3 is a similar view showing the same shank projected; Fig. 4 is a transverse section as seen along the plane indicated by the line 4-4 of Fig. 2; Fig. 5 is a similar view as 45 seen along the plane indicated by the line 5-5 of Fig. 3; Fig. 6 is a perspective view of one of the tool shanks and parts carried thereby.

In these drawings, the numeral 1 indicates a tubular magazine having at one end a chuck member 2 provided with a poly-sided central opening 3. The portion of the magazine 1 adjacent the chuck member 2, is provided with a plurality of longitudi-

nally disposed parallel slots 4, while on opposite sides of the front ends of these slots, openings 5 are formed through the magazine. The walls of the openings 5 constitute stop shoulders for engagement by stop members yet to be described. 55

Confined in the magazine 1 to be independently projected from one end thereof, is a plurality of tool shanks 6 which are positioned eccentrically and held in contact with the wall of said magazine, by the 60 spring arms 7 which are integrally joined at their rear ends to the rear ends of said shanks, the front ends of said arms being bent laterally as disclosed at 8 to provide studs projecting through the several slots 4. 70 The studs 8 pass through openings in leaf springs 9 and are either upset or provided with suitable nuts, the latter being shown in the present application. In the present embodiment of the invention, the springs 9 75 are shown as formed by striking the intermediate portions of a plurality of slide plates 10 outwardly, such plates being disposed over the slots 4 in sliding contact with the magazine 1. 80

It is the intention of the invention to project any one of the shanks 6 through the poly-sided opening 3 in the chuck 2, and for so doing the inner end of said chuck is provided with a conical socket 11 into which 85 the front ends of the several shanks project in spaced relation. It is from the apex of the socket 11, that the opening 3 leads, it being thus evident that when one of the slides 10 is shifted in the proper direction, the 90 shank 6 having connection with said slide will be projected forwardly, during which movement the front end of such shank comes into contact with the inclined wall of the socket 11 and is thus gradually directed to 95 the opening 3, the spring 7 allowing the shank 6 to move in this manner as clearly disclosed in Fig. 3.

For locking the shanks 6 in projected position, stops 12 are formed on channel-shaped members 13, the latter being disposed astride on the front ends of the spring arms 7 and having openings through which the studs 8 project, the stops 12 being disposed for reception in the openings 5 when 105 the shanks are projected, whereby retraction of the shank in use is prevented until the spring 9 having connection with such

shank is forced inwardly by the thumb of the user. When this is done, however, the spring arm 7 is forced inwardly, thus retracting the stops 12 from the opening 5 and allowing the shank to be again withdrawn by proper actuation of its slide.

The several shanks are of poly-sided formation conforming to the shape of the opening 3, whereby when once projected, all strain for preventing rotation of the shanks independently of the magazine, will be exerted on the chuck member 2 rather than upon the spring arms 7. In the present embodiment of the invention, the several shanks 6 are shown as provided with rectangular keys 14 which are used for the winding of watch movements and are commonly termed "bench keys". These keys are of assorted sizes and in order that the proper key may be projected, the several slides 10 are inscribed with indicating characters as disclosed at 15, whereby the jeweler may ascertain at a glance which slide must be operated to project the necessary tool.

The end of the magazine opposite that provided with the chuck 2, is shown in the present embodiment of the invention as equipped with an additional chuck 16 which preferably includes a pair of jaws 17 forced together by spring pressure and capable of being released by proper actuation of a circular slide 18 which surrounds the magazine 1. It is to be understood that the device 16 is mounted upon the magazine only for the sake of convenience and that the operation of the tool as previously described is affected in no manner by the presence of such device.

From the foregoing description, taken in connection with the accompanying drawings, it will be evident that although a very simple and inexpensive construction has been provided, the device will be highly efficient and durable and will possess a number of advantages.

In the drawings, certain specific details of construction have been shown for accomplishing probably the best results and in the preceding, such details have been described, but it will be evident that I need not be limited thereto otherwise than to that extent to which the appended claims restrict me. Furthermore, although the improved tool has been defined as constructed for use of jewelers and watchmakers, it will be evident that numerous other devices could be well provided in place of the keys 14, and that the entire tool could well be made in such proportions as to accommodate such instruments as screw drivers, drills, etc.

I claim:

1. A tool comprising a tubular magazine, a chuck carried by one end of said magazine and having a central opening leading from

the interior thereof, a plurality of tool shanks confined eccentrically in the magazine and shiftable independently therefrom into the opening in the chuck, slides on the exterior of the magazine for projecting said shanks, and spring means connecting the slides and the shanks.

2. A tool comprising a tubular magazine, a chuck carried by one end of said magazine and having a central opening leading from the interior thereof, a plurality of tool shanks confined in the magazine and shiftable independently therefrom into the opening in the chuck, slides disposed on the exterior of the magazine, and spring arms united at their opposite ends to the innermost ends of the shanks and to the slides.

3. A tool comprising a tubular magazine having longitudinally disposed slots, independent slides moving over said slots, an apertured chuck at one end of the magazine, a plurality of tool shanks confined eccentrically in the magazine and shiftable therefrom into the chuck, and yielding connections between the slides and the shanks extending through the aforesaid slots.

4. A tool comprising a tubular magazine having stop shoulders accessible from its interior, a plurality of tool shanks confined in said magazine to be projected from one end thereof, slides for projecting said shanks, and spring pressed stops movable with said shanks for coaction with the aforesaid stop shoulders to lock the shanks in projected position.

5. A tool comprising a tubular magazine having stop shoulders accessible from its interior, slides on said magazine having outwardly extending springs, a plurality of tool shanks confined in the magazine to be projected from one end thereof and having portions connected to the springs of the slides, and stops on such portions of the shanks for engagement with the aforesaid stop shoulders to lock the shanks in projected position.

6. A tool comprising a tubular magazine provided with parallel longitudinally disposed slots, and having stop shoulders accessible from its interior, slides operating over said slots and having portions bowed outwardly to provide springs, a plurality of tool shanks confined in the magazine to be projected from one end thereof and having portions connected to the aforesaid springs, and stops on such portions for engagement with the aforesaid stop shoulders to lock the shanks in projected position.

7. A tool comprising a tubular magazine provided with parallel longitudinally extending slots and having stop shoulders accessible from its interior, slides operating over said slots and having outwardly extending springs, a plurality of tool shanks confined in the magazine to be projected

from one end thereof, spring arms secured at one end to said shanks and having their opposite ends bent laterally through the slots and secured to the aforesaid springs, channel-shaped members straddling portions of said arms and having openings through which the laterally bent ends thereof project, and stops on said channel-shaped members for coaction with the aforesaid stop

shoulders for locking the shanks in projected position.

In testimony whereof I have hereunto set my hand in presence of two subscribing witnesses.

ALFRED A. TURNAGE.
